UNITED STATES PATENT OFFICE.

FREDERICK ERFLE, OF PHILADELPHIA, PENNSYLVANIA.

FLANGE-FACING ATTACHMENT.

Application filed July 22, 1926. Serial No. 124,123.

My invention relates to facing machines and more particularly to attachments for facing the flanges of large pipe.

The principal object of my invention is to provide an attachment which may be readily secured to the face plate of a lathe or similar machine tool.

A further object is to so construct the attachment that it is easily operated and may be adjusted to face the flanges with the greatest precision.

These objects, and other advantageous ends which will be described hereinafter, I attain in the following manner, reference being had 15 to the accompanying drawings in which

Figure 1 is a fragmentary plan view of a lathe on which my attachment has been installed and showing a section of pipe secured to the lathe,

20 Figure 2 is an elevation of the lathe shown in Figure 1,

Figure 3 is a front view of the face plate shown in Figure 1, drawn on an enlarged scale,

25 Figure 4 is a side view of the grinding bracket taken on line 4—4 of Figure 3,

Figure 5 is a section on line 5—5 of Figure 4, Figures 4 and 5 being drawn to a still larger scale,

30 Figure 6 is an enlarged view of the tool post, taken on line 6—6 of Figure 3,

Figure 7 is a fragmentary sectional view of a pipe and flange, and

35 Figure 8 is a sectional view taken on line 8—8 of Figure 3, Figures 7 and 8 being drawn on a larger scale than Figure 3.

Flanges for large pipe are usually faced and the inner corner chamfered as shown at 40

9 in Figure 7 and two slight grooves are cut in the inner wall of the flange as indicated at 10. The pipe is then put in a machine and the metal pressed into the grooves 10 and over the chamfered part 9 by means of rollers working under heavy pressure. This dis-

45 torts the face of the flange to such an extent that a tight joint cannot be made. Consequently it is necessary to face the part 11, usually by hand, either by scraping or ston-

50 ing. The parts 12 and 13 have originally been turned down lower than the part 11 so that when finished there will be a difference in elevation of approximately .005 of an inch. The principal object of my invention is to overcome this hand work and to so accurately

55 finish the flange that perfect joints are possible when the pipes are assembled.

Referring more particularly to the drawings, 14 represents the face plate of an ordinary lathe. Only a part of the lathe has been shown and none of it will be described as it 60 is a well known machine and forms no part of my invention. 15 is a grinder secured in one of the slots of the face plate by means of bolts 16. The grinder consists of a flanged bracket 17, having a longitudinal groove 18, 65 on which is mounted a sliding block 19 having a tongue 18^a, engaging the groove 18, and shoulders 20, between which a bearing block 21 is slidably mounted and held in place by gibs 22. The shoulders 20 are slightly less 70 in height than the base section 23 of the bearing block 21 so that when wing nuts 24 are tightened down on the screws 25, the gibs 22 will pinch the base section between the gibs and the top of the sliding block 19. The 75 block 19 is secured against transverse movement by means of the bolt 27 which passes through slot 28 in the bracket 17. Transverse adjustment is obtained by means of the screw 29 which passes through a bearing 30 80 in an angle 31, which is bolted to the bracket 17 by means of the bolts 32. The screw 29 is held against longitudinal movement by the hand wheel 33 and collar 33^a abutting opposite sides of the angle 31. A set screw 34 85 is provided for holding the screw 29 against rotation. The screw 29 engages a threaded aperture 35 in the block 19 and a nut 36 is provided for additional locking means. Mounted in the bearing block 21 is a shaft 37, 90 on the shouldered outer end of which is secured a grinding wheel 38 by means of a nut 39. Pulley 40 is mounted near the center of the shaft and rotates between the two bearing portions 41 of the block 19. The 95 bearing block 21 is adjusted longitudinally by means of the screw 42 engaging a threaded aperture 43 in bearing sections 41 and being secured between the collar 44 and the hand-wheel 45 located on either side of the flange 100 46 which forms a part of block 19. Motion is imparted to the grinding wheel 38 by means of a belt 47 passing over pulley 40 and engaging a larger pulley 48 mounted in one of the slots of the face plate. Secured to pulley 105 48 is a smaller pulley 50, which is driven by belt 51 passing over a pulley attached to the motor 52 which is secured in one of the slots of the face plate; the motor pulley being larger than pulley 50. Slack in the belt 51 110 is taken up by means of pulley 53 mounted on a standard 54 attached to the face plate 14.

Slack in the belt 47 is taken up by means of a spring actuated tensioning device 55, illustrated in Figure 8. It consists of a bracket 56 having slotted holes 57 through which it is secured in one of the slots of the face plate. Tubular arm 58 extends through an aperture 59 in the bracket 56 and is secured therein in any suitable manner. Within the tube is a shouldered plunger 60 having a coiled 10 spring 61 surrounding its reduced portion, and bearing against the shoulder 62 and a plate 63 secured to the bracket by means of bolts 64. The outer end of the plunger 60 is bifurcated and a pulley 65 is secured in 15 this portion by means of a pin 66. The plunger is held against rotation by means of a bolt 67 passing through the arm 58 and through a slot 68 in the plunger. While I have described this type of spring idler 20 other types would answer the purpose equally well.

While the grinder shaft might be connected to the motor by other means, I prefer the belt and pulley connection with the motor somewhat remote from the grinder bracket as it permits distribution of the weight on the face plate and a wide range of adjustment.

The device is operated in the following manner:

30 After the flange has been rolled onto the pipe, the pipe is placed on the lathe with one end secured to the lathe carriage in any suitable manner and the rear end supported on suitable blocking. The carriage is advanced 35 toward the face plate to approximately the correct distance and, by rotating the face plate in the proper direction, a cut is taken across the flange with a tool 69 secured in a tool post 70, which has not been described as 40 it is a well known construction. When it is evident that all portions of the surface 11 are in the same plane, the portions 12 and 13

are turned down approximately .005 of an inch below the portion 11. The tool 69 is then backed up and the grinding wheel 38 45 adjusted, by means of the screws 42 and 29, so that it will grind and polish the portion 11 of the flange to an absolutely true surface.

By adjustably mounting all parts of my facing attachment in the usual slots of the 50 face plate of a lathe or similar machine tool the attachment is adapted for use upon flanges of a wide range of sizes of pipes.

While I have described my attachment in detail, I wish it understood that it is subject to such changes as fairly come within the scope of the appended claim.

I claim:

A flange facing attachment for lathes consisting of a bracket adapted to be adjustably secured in one of the slots of the face plate of a lathe; a block slidable thereon in a plane parallel to the face plate; a bearing block slideable on the first named block in a plane perpendicular to the face plate; a shaft carried by the last named block; a grinding wheel fixed to the shaft; means for adjusting the position of the blocks; means for locking them in adjusted position; a motor adapted to be secured in one of the slots of the face plate and a pulley on the motor shaft; a pulley mounted in the bearing block; an intermediate pulley adjustably mounted in one of the slots in the face plate, belts connecting the pulley on the motor shaft with the intermediate pulley and the intermediate pulley with the pulley in the bearing block; means mounted in slots in the face plate for tightening the belts, and means for actuating the motor.

In testimony whereof I have signed my name to this specification.

FREDERICK ERFLE.
